UNITED STATES PATENT OFFICE

166,887

COMBINATION VENDING AND DISPLAY
STAND FOR HAIR CUTTERS

Abraham N. Spanel, Princeton, N. J., assignor to Cutler Corporation, Wilmington, Del., a corporation of Delaware

Application February 11, 1952, Serial No. 18,469

Term of patent 14 years

(Cl. D52—2)

To all whom it may concern:

Be it known that I, Abraham N. Spanel, a citizen of the United States and a resident of Princeton, in the county of Mercer and State of New Jersey, have invented a new, original, and ornamental Design for a Combination Vending and Display Stand for Hair Cutters, of which the following is a specification, reference being had to the accompanying drawing, forming part thereof, wherein

The figure is a perspective view of a combination vending and display stand for hair cutters, showing my new design. The portion of the design not shown in said perspective view is the same in appearance as the diametrically opposite part that is shown.

I claim:

The ornamental design for a combination vending and display stand for hair cutters, substantially as shown and described.

ABRAHAM N. SPANEL.
